Primary Examiner — April Rivas*Assistant Examiner* — Tia Ruth-Renee Polidori*(74) Attorney, Agent, or Firm* — Reilly International Property Law Firm(57) **CLAIM**

The ornamental design for a vertical hanger system as shown and described.

DESCRIPTION

FIG. 1 is a top perspective view of our new design for a vertical hanger system shown in a configuration of use with an environmental barrel;

FIG. 2 is a top plan view of our new design for a vertical hanger system shown in isolation for clarity of disclosure; FIG. 3 is a front elevation view thereof; the rear elevation view being identical thereto;

FIG. 4 is a top perspective view thereof;

FIG. 5 is a bottom plan view thereof;

FIG. 6 is a left side elevation view thereof;

FIG. 7 is right-side elevation view thereof; and,

FIG. 8 is an exploded view thereof showing order of assembly.

The broken line portions of FIG. 1 are included to show environment that forms no part of the claimed design.

1 Claim, 6 Drawing Sheets(56)
